(57) **CLAIM**

The ornamental design for a clip for identifying elongated objects, as shown and described.

DESCRIPTION

FIG. 1 is a top perspective view of the clip for identifying elongated objects showing my new design;

FIG. 2 is a bottom perspective view thereof;

FIG. 3 is a top view thereof;

FIG. 4 is a bottom view thereof;

FIG. 5 is an enlarged right side view thereof;

FIG. 6 is a left side view thereof;

FIG. 7 is a front view thereof; and,

FIG. 8 is a back view thereof.

The broken line representations of portions of the remainder of the clip for identifying elongated objects in FIGS. 1-8 form no part of the claimed design.
